THERMIONIC AMPLIFIER

Samuel Ruben, New Rochelle, N. Y., assignor to
 Sirian Lamp Company, Newark, N. J., a corporation of Delaware

Application August 23, 1930, Serial No. 477,304

5 Claims. (Cl. 250—27.5)

This invention relates to thermionic amplifiers or relays and particularly to that type of device which depends for operation on the ionization of a gas.

5 One of the objects of the invention is to provide an amplifier which will carry relatively large amounts of plate current.

Another object of the invention is to provide an amplifier which will operate at relatively low plate voltage.

10 Other objects of the invention and objects relating particularly to the construction and assembly of the various parts will be apparent as the description of the invention proceeds.

15 The invention is illustrated in the accompanying drawings in which:

Fig. 1 is a perspective view partly in section of my improved amplifier tube;

Fig. 2 is a longitudinal sectional view, somewhat enlarged, of one end of the element or cathode shown in the construction of Fig. 1;

Fig. 3 is a circuit diagram showing the use of the amplifier; and

Fig. 4 is a front sectional view of a modified form of the device.

Referring now more specifically to the drawings the embodiment of the invention shown in Fig. 1 comprises an envelope 10 mounted on the usual press 11 which may be formed integral with the envelope to support the various elements of the device. The elements comprise a cathode 12, a grid 13, and an anode 14. The cathode may comprise a coil 15 of resistance wire such as tungsten, molybdenum, tantalum, or nichrome, which may be closely wound to form a concentrated filament coil as indicated in Fig. 2. The outer surface of the coil may be coated with electron emitting material 16 which may be any of the materials commonly used for that purpose such as the oxides of the alkali metal group or mixtures of such oxides. Such material may be mixed with a suitable binder and applied to the outer surface of the coil by any desired means such as a brush and then dried in position.

45 The coil 15 may be supported at its lower end upon a short support rod 17 which may be sealed in the press 11 while the upper end of the coil may be supported upon a rod 18 which may be bent rearwardly, downwardly, and inwardly again where it may also be sealed in the press 11. A glass bead 19 may be attached to the rod in back of the element 12 either by being sealed on to the support rod or having a short angular support rod 20 welded to the support rod and sealed in

end of the other elements insulatedly with respect to each other.

5 The grid 13 may comprise a helical coil 21 of fine wire such as molybdenum wire which may be welded to two support rods 22 and 23. The diameter of the coil may be somewhat larger than the element 12 so that it may be spaced from the element but mounted concentrically therewith. The support rod 22 may be connected at its lower end to a relatively short support rod 24 which may be sealed in the press 11 while the upper end of the support rod 23 may be welded to a connecting rod 25 which may extend rearwardly and then be bent downwardly to be sealed into the bead 19.

10 The anode 14 may be formed of two semi-cylindrical plates having flanges 26 radially extending at the sides thereof which may be welded together to form a complete cylindrical anode which is preferably larger than the grid so as to be spaced from it but mounted concentrically with the grid and cathode. The flanges 26 may be provided with grooves 27 adjacent the outer edges to receive the support rods 28 which may be sealed in the press 11 at their lower ends and may extend 15 upwardly through the grooves 27 being welded to the flanges 26. The rods 28 may also be bent 20 backwardly above the anode 14 and downwardly again where the ends may be sealed in the bead 19. In this manner the cathode, grid, and anode are 25 securely mounted on the press 11 in spaced relation with each other and rigidly so as to avoid any movement with respect to each other.

30 The envelope may be filled at a pressure of about 200 mm. with an ionizable gas and preferably one of the monatomic gases such as argon, helium, neon, krypton, or xenon.

35 After the elements are mounted as shown in Fig. 1 with the press formed integral with the envelope, the envelope may be connected in the usual manner to an exhaust pump and an oven placed over it to raise the temperature thereof to between 350 to 400° C. or as high a temperature as the parts will stand without injury. This drives out occluded gases from the various parts 40 and the exhaust pump withdraws the gases as they are driven out. During this time a current may be run through the element 12 to raise the temperature to approximately 600° C. to drive out some of the occluded gases. This treatment 45 is continued until no more gas appears in the tube as is evidenced by the lack of fluorescence when high tension current is directed against the walls of the bulb from an induction coil. A high vacuum of about .5 micron is preferably obtained. 50 55

The current through the filament may then be increased so that the temperature is slowly raised until it is about 800° C. with a bright red color. This heating tends to drive out the binder in the 5 electron emitting material and other occluded gases which have not already been released, the vacuum pump drawing the gases out as they are driven from the various parts. When no more gases are found in the bulb the oven may be raised 10 and the filament heated to slightly less than 1200° C., the pump being connected all this time to remove any gases driven off and maintain the vacuum.

The pump may then be shut off and the filament current turned off and a slight amount of 15 an inert gas such as neon gas at about 1/2 mm. pressure may be admitted to the bulb and the filament current turned on and gradually increased. Spots of localized discharge will then 20 appear having a reddish color and these spots will gradually spread until a diffused glow completely fills the bulb. This process appears to 25 activate the electron emitting coating and may be maintained until the discharge is uniform throughout the entire bulb which usually takes less than ten minutes. During this time the current on the filament should not be raised too 30 high so that the coating will not be destroyed or thrown off from the filament. If white discharge spots appear on the filament or support rod it is an indication that there are more gases or 35 vapors in the bulb and the bulb should again be exhausted and the whole process of activation repeated.

When the activation is completed the filament 40 temperature may be raised to about 1400° C. for a moment and then the vacuum pump connected again to remove any undesirable gases which may have been thrown off during the activation process.

When the high vacuum is again obtained the filament circuit may be disconnected, the pump turned off, and about 50 mm. of neon gas may be admitted to the bulb followed by about 150 mm. 45 of argon. The bulb may then be sealed off and cleaned up by flashing magnesium therein.

Magnesium may be introduced into the bulb 50 by attaching it to a small container 30 which may be connected by means of a wire 31 to one of the support rods as the support rod 28 in the tube. When the magnesium has been flashed the tube is ready for use.

When current is run through the element supports the emission of electrons therefrom appear 55 to ionize the region in the vicinity thereof thus producing a conducting path from one end of the element to the other and a gaseous discharge appears around the element like a halo. The size of this discharge or halo may be controlled by the 60 grid 13 as when it has a negative potential the discharge tends to collapse while when it has a positive potential the area of the discharge tends to increase. As the region of discharge forms a 65 conducting path through the gas it will conduct a large amount of current between the cathode and anode when the discharge is large enough to include the anode. Hence, a large amount of plate current may be modulated by a slight variation of potential on the grid.

The amplifier may be used in the usual manner as indicated in Fig. 3 where the grid 13 is connected through an input transformer 32 to the negative side of the A battery 33 which may be connected through a suitable rheostat 34 to the 75 cathode 12. The anode 14 may be connected

through the output transformer 35 to the positive side of a B battery 36.

Due to the conducting path between the anode and cathode when the discharge includes the two the tube will carry a large amount of plate current. It is necessary however to have sufficient voltage on the cathode to give a potential drop along the surface to ionize the gas in the tube. The voltage should be at least thirty volts for best results.

It may be desirable to have the device operate to control a local circuit which is entirely independent of the cathode and grid and if so the construction shown in Fig. 4 may be used. Here a cathode 37 may be supported upon a short support rod 38 at the lower end thereof which may be sealed in the press 39 while the upper end may be supported on a rod 40 which may be bent rearwardly and downwardly and inwardly again where it may be sealed in the press 39 similarly to the rod 18 as shown in Fig. 1. A grid 41 may be formed similarly to the grid 13 of Fig. 1 and may be supported at its lower end by means of the support rod 42 sealed in the press 39 and at its upper end by means of the rod 43 which 25 may extend rearwardly and be bent downwardly where it may be sealed in a bead 44 secured to the support rod 40 in a manner similar to the bead 19 of Fig. 1.

A pair of cylindrical electrodes 45 and 46 may 30 be positioned around the grid 41 but spaced longitudinally as indicated. The electrode 45 may be formed of a strip of metal with a flange 47 extending radially from one side thereof. This flange may be welded to a support rod 48 which 35 may be sealed in the press 39 and may extend upwardly beyond the upper end of the electrode 45 where it may be connected to a short angular support rod 49 which may be sealed in the bead 44. In like manner the electrode 46 may have a 40 radially extending flange 50 which may extend in the opposite direction from the flange 47 and may be welded to a support rod 51 which may extend downwardly spaced from the electrode 45 and 45 may be sealed in the press 39. The upper end of the support rod 51 may be welded to a short angular support rod 52 which may be bent rearwardly and downwardly and may be sealed in the bead 44.

A leading-in wire 53 may be connected to the 50 support rod 48 while another leading-in wire 54 may be connected to the support rod 51 thus connecting the electrodes 45 and 46 respectively. The leading-in wires 55 and 56 may be connected to the rods 48 and 50 respectively to form the 55 connection for the cathode while a leading-in wire 57 may be connected to the grid support rod 52.

If then the grid connector 57 is connected by means of a wire 58 to an input circuit 59, the other side of which is connected by means of a 60 wire 60 to the negative side of an A battery 61 which may be connected across the cathode terminals 55 and 56 by the wires 62 and 63 respectively, then a modulation of the input circuit 59 will cause a change in the conductivity between 65 the two electrodes 45 and 46. Hence, if these electrodes are connected in a local circuit by connecting the leads 53 and 54 by wires 64 and 65 including a battery 66 and a translating device 67 current will flow in the local circuit and through 70 the translating device as the conducting path between the electrodes 45 and 46 changes.

While I have shown a cathode which is comprised of a concentrated coil of wire other types of cathodes may be used as for instance a single 75

straight wire coated with electron emitting material although I prefer to use a large potential drop between points on the emitting surface, if possible, and hence I prefer to use a coil for this purpose. Also while the coating of electron emitting material has been shown as a solid coating on the surface of the coil it will be evident that the individual turns of the coil may be coated separately if desired.

10 While I have described the tube as being filled with neon and argon gas other gases may be used such as those mentioned above which may be preferable because of their monatomic structure. If desired also the conductivity of the 15 gas may be increased by adding a small amount of metal vapor such as the vapors of mercury, rubidium, or caesium and these metal vapors may be introduced into the bulb by providing a small quantity of a salt of the desired metal, 20 such as a chloride, upon the container 30 adjacent the magnesium. When the magnesium is flashed it reacts with the salt liberating the metal which condenses on the inner wall of the bulb to be evaporated again when the tube is operated.

Also while a certain specific structure has been shown and described it is to be understood that this is for the purposes of illustration and that the amplifier is intended to include any structure 30 in which a current between a cathode and an anode is modulated by a grid and which makes use of the ionization of the gas in the vicinity of a continuous conductor cathode.

Many other modifications of the invention may 35 be resorted to without departing from the spirit thereof, and I do not therefore desire to limit myself to what has been shown and described except as such limitations occur in the appended claims.

40 What I claim is:

1. An amplifier comprising an electron emitting cathode, a grid spaced from said cathode, an anode spaced from said grid, and an ionizable gas surrounding said cathode, grid, and anode, 45 and comprising a mixture of argon and neon gas and having a pressure of approximately 200

mm. of mercury, the breakdown potential of said gas per unit length of the cathode when subjected to electron bombardment being less than the potential per unit length necessary to raise the cathode to operating electron emitting temperature, and an envelope including said cathode, grid, anode, and gas.

2. An amplifier comprising an electron emitting cathode, a grid spaced from said cathode, an anode spaced from said grid, and an ionizable 10 gas surrounding said cathode, anode, and grid, and comprising approximately 25% of neon and approximately 75% of argon and having a pressure of approximately 200 mm. of mercury.

3. An amplifier comprising a filamentary resistance wire, a coating of electron emitting material upon the surface of said wire, a grid spaced from said wire, an anode spaced from said grid, and an ionizable gas surrounding said wire, grid, and anode, and comprising approximately 25% 15 of neon and 75% of argon and having a pressure of approximately 200 mm. of mercury.

4. An amplifier comprising a filamentary wire wound in the form of a coil, a coating of electron emitting material upon the surface of said 25 coil, a grid spaced from said coil, an anode spaced from said grid, and an ionizable gas surrounding said coil, grid, and anode, and containing approximately 25% of neon and 75% of argon 30 and having a pressure of approximately 200 mm. of mercury.

5. A relay comprising an electron emitting cathode, a grid spaced from said cathode, a pair of electrodes spaced from said grid, and an ionizable gas surrounding said cathode, grid, and electrodes, and containing argon and neon and having a pressure of approximately 200 mm. of mercury, the breakdown potential of said gas per unit length of the cathode when subjected to 35 electron bombardment being less than the potential per unit length necessary to raise the cathode to operating electron emitting temperature, and an envelope including said cathode, grid, anode, and gas.

SAMUEL RUBEN. 45
